United States Patent Office

Des. 183,899
Patented Nov. 11, 1958

183,899

RAZOR

Hyman I. Pressman and Donald Pressman,
Cleveland, Ohio

Application October 4, 1957, Serial No. 47,975

Term of patent 14 years

(Cl. D22—3)

FIG. 1

FIG. 3

FIG. 2

Fig. 1 is a side perspective view of a razor showing our new design, the sides opposite thereto being substantially similar in appearance;

Fig. 2 is a bottom plan view; and

Fig. 3 is a side elevational view thereof.

We claim:

The ornamental design for a razor, substantially as shown and described.
